UNITED STATES PATENT OFFICE.

RAYMOND S. PARSONS, OF EAST HAMPTON, NEW YORK.

OUTLET-BOX, ELECTRIC CONDUCTOR.

No. 845,974.

Specification of Letters Patent.

Patented March 5, 1907.

Application filed November 12, 1906. Serial No. 348,128.

To all whom it may concern:

Be it known that I, RAYMOND S. PARSONS, a citizen of the United States, residing at East Hampton, in the county of Suffolk and State of New York, have invented a new and useful Outlet-Box, Electric Conductor, of which the following is a specification.

This invention relates to outlet or juncture boxes of that general class employed for housing the terminals of armored conductors used in installing electric wires for lighting and other purposes.

The object of the invention is to provide an outlet-box having a plurality of radial wire-receiving tubes or bushings formed integral therewith, thus dispensing with the employment of detachable couplings and similar fastening devices for retaining the wires or conductors within the box.

20 A further object is to form the tubes or bushings with annular shoulders adapted to engage the adjacent ends of the flexible armor, thereby to limit the movement of the same.

25 A further object is to provide means for clamping the conductors or wires within the tubes and, further, to provide the inner ends of the tubes with curved or rounded terminals, so as to prevent injuring the conductors when 30 the latter are threaded through said tubes.

35 A still further object of the invention is to generally improve this class of devices so as to increase their utility, durability, and efficiency, as well as to reduce the cost of manufacture.

With these and other objects in view the invention consists in the construction and novel combination and arrangement of parts hereinafter fully described, and illustrated in 40 the accompanying drawings, it being understood that various changes in form, proportions, and minor details of construction may be resorted to within the scope of the appended claims.

45 In the accompanying drawings, forming a part of this specification, Figure 1 is a longitudinal sectional view of an outlet or juncture box constructed in accordance with my invention, showing the same in position on a wall or partition. Fig. 2 is a front elevation of the same detached.

Similar numerals of reference indicate corresponding parts in all of the figures of the drawings.

50 The improved outlet-box is principally designed for use in installing concealed wires or

conductors for electric lights in houses and other buildings, and by way of illustration is shown in position on the wall or partition of a building of the ordinary construction, in 60 which 5 designates one of the vertical studs or beams, 6 the laths, and 7 the plaster.

The device consists of a metallic casing or housing 8, preferably circular in form, as shown, and having one end thereof open and 65 its side walls provided with a plurality of radiating openings or recesses 9 for the reception of the conductors.

Disposed entirely within the casing 8 at each wire-receiving opening 9 and preferably 70 formed integral with said casing is a tubular member or bushing 10, having a longitudinal bore 11 formed therein for the reception of the electric conductor, there being an annular shoulder 12 arranged at the inner end of each 75 tubular member and adapted to bear against the end of the adjacent flexible armor, thereby to limit the inward movement of the same. The inner ends of the tubes or members 10 are curved or rounded, as indicated at 13, so 80 as to prevent abrading or otherwise injuring the adjacent terminals of the conductors when the latter are threaded through the members 10 for connection with the electric lights.

85 The members 10 are each provided with a flat surface 14, and threaded through the walls of said members at the flattened portions 14 thereof are suitable clamping members, preferably in the form of screws 15, 90 which bear against the exterior walls of the flexible armor when the latter is positioned within the tubes or members 10, and thus serve to prevent accidental displacement of the same.

95 The several members or tubes 10 are connected by a supporting member 16, having one end thereof threaded, as indicated at 17, for engagement with the corresponding threads of an electric-light fixture of the usual construction, while the opposite end thereof is provided with a plurality of radiating arms 18, the free ends of which are bent laterally at 19 for engagement with the flattened portions 14 of the members 10, there 105 being screws or similar fastening devices 20 threaded through the perforations in the arms 19 and the adjacent walls of the members 10 for securing the pipe or support 16 in position on the box or casing.

110 The casing 8 is preferably retained in position on the stud 5 by means of screws or

similar fastening devices 21, which pass through suitable openings 22, formed in one wall of the casing 8, and are screwed or otherwise embedded in the stud 5, as shown.

- 5 In using the device the covered conductors are inserted through the openings 9 and seated in the tubes or members 10 with the adjacent end of the flexible armor bearing against the shoulders 12 and with the terminals of the conductors or wires passed under the support and thence extended laterally between the arms 18 for connection with the electric-light fixture. When only one of the openings 9 are used, the adjacent openings may be 15 plugged by inserting suitable pieces of metal cut to fit the same.

While the outlet-box is principally designed for use when wiring finished houses, it is obvious that the same may be installed in a 20 house or other building at the time the same is erected.

Attention is called to the fact that the intermediate portions of the arms are curved or bowed laterally, so as to allow ample space 25 between the arms and the bottom of the box to permit the passage of the wires.

It will of course be understood that the usual canopy or ornamental casing may be employed to cover the open end of the housing 8, so as to give the same a neat attractive 30 appearance, and that the outlet-box may be positioned in the wall, ceiling, or other portion of the building.

Having thus described the invention, what 35 is claimed is—

1. An outlet-box including a casing having an opening formed therein, a wire-receiving member disposed entirely within the casing at said opening and provided with a stop-shoulder, and means piercing the walls of said member and engaging the wire for clamping the latter within said member.

2. An outlet-box including a casing having an opening formed therein, a tubular wire-receiving member disposed entirely within the casing at said opening, and having its inner end curved or rounded and its interior walls provided with a stop-shoulder, and means for clamping the wire within the tubular member.

3. An outlet-box including a casing having an opening formed in the walls thereof, a

tubular wire-receiving member disposed at said opening, a supporting member rigidly secured to said wire-receiving member, and means carried by the wire-receiving member and adapted to engage the wire for preventing accidental displacement of the same.

4. An outlet-box including a casing provided with a plurality of openings, tubular wire-receiving members formed integral with the casing and extending inwardly from the latter at said openings, and means piercing the walls of the members and engaging the wires for locking the same against accidental displacement.

5. An outlet-box including a casing having its side walls provided with a plurality of openings, tubular wire-receiving members disposed at said openings and each having one terminal thereof curved or rounded and its interior walls provided with a stop-shoulder, a supporting member having radiating arms for attachment to the tubular members, and means piercing the tubular members and engaging the wires for locking the same within in said members.

6. An outlet-box including a casing having one end thereof open and its side walls provided with a plurality of openings, tubular wire-receiving members disposed at said openings and each having one end thereof curved or rounded and its interior walls provided with an annular stop-shoulder, there being a flattened portion formed on each member, a supporting member having one end thereof threaded and its opposite end provided with radiating arms having laterally-perforated extensions bearing against the flattened portions of the tubular members, fastening devices passing through the perforations in the extensions and engaging the tubular members, and clamping-screws threaded in the walls of the tubular members and adapted to engage the wires for locking said wires in engagement with the tubular members.

In testimony that I claim the foregoing as my own I have hereto affixed my signature in the presence of two witnesses.
